UNITED STATES PATENT OFFICE

2,212,697

REGENERATIVE FURNACE

Peer D. Nielsen, Lorain, Ohio, assignor to National Tube Company, a corporation of New Jersey

Application June 30, 1939, Serial No. 282,246

2 Claims. (Cl. 263—15)

This invention relates to regenerative melting furnaces, and more particularly to the checker chambers thereof which are employed for pre-heating the air or gas used for combustion purposes, whether the furnace be fired with gas, oil or tar.

In conventional designs, the checker chamber is filled from end-to-end with brick checkerwork, through the openings of which waste gases and air or gas alternately pass during the periods between furnace reversals. Suitable spaces are provided above and below the checkerwork to allow for distribution of gas and air above and below the openings passing through the checkerwork; to facilitate blowing out dust which collects in the openings in the checkerwork; for periodic replacement of the top courses of brick; and for the accumulation of dust in flues below the checkers.

When the furnace is operating, waste gases enter the checker chamber through an inlet and, after giving up a portion of their heat to the checkerwork, pass out of the chamber to the furnace stack through an outlet. Likewise, when the furnace is reversed, air or gas enters the chamber through the outlet and, being pre-heated in traveling through the checkerwork, passes to the furnace through the inlet.

As previously stated, in the conventional design of checker chamber the checkerwork is continuous over the length of the chamber and therefore abuts against the bulkhead at the cold end of the chamber, or the end remote from the furnace.

On account of the use of this type of construction it is necessary, in order to get at the checkerwork for thorough cleaning and removal of the dust which accumulates in the flues below the checkers, to remove all checkerwork for a distance of several feet back from the bulkhead on the cold end. This operation, usually carried on whenever the furnace is rebuilt, involves the removal and relaying of several thousand bricks simply to gain access to the flues and provide room for cleaning that part of the checkerwork not removed from the chamber.

A further disadvantage of this conventional type of construction is that it is not possible to reach the corners of the checkerwork, adjacent to the bulkhead on the cold end of the chamber, for cleaning by means of air or water while the furnace is operating. These corners are inaccessible because of the fact that a small opening only can be made in the bulkhead, when the

furnace is hot, for insertion of cleaning equipment.

It is among the objects of the present invention to provide a regenerative melting furnace which is cheap and easy to recondition or rebuild.

Another object is to provide a checker chamber of the type described which is more efficient in operation than the checker chambers of the prior art.

The invention, then, comprises the features hereinafter fully described and as particularly pointed out in the claims, the following description and the annexed drawings setting forth in detail the certain illustrative embodiment of the invention, this being indicative of but one of a number of ways in which the principles of the invention may be employed.

In said drawings:

Figure 1 is a plan of the checker chamber of the invention;

Figure 2 is a sectional elevation on the line II—II of Figure 1; and

Figure 3 is a sectional view on the line III—III of Figure 2.

Referring more particularly to the drawings, the numeral 2 designates the floor line above and below which the checker chamber of the invention is to be built.

The checker chamber comprises a pair of spaced vertical side walls 3 which support a roof 4. At one end of the walls 3 and the roof 4, the checker chamber embodies a removable bulkhead 5 which provides ready access to the interior of the chamber for the purposes of rebuilding or inserting cleaning tools, as will appear more fully hereinafter.

The checker chamber of the present invention provides, adjacent the end having the removable bulkhead 5 and spaced several feet therefrom, a division wall 7 which extends the full width of the chamber but is spaced from the roof 4. Between the division wall 7 and the opposite end of the checker chamber is provided a space within which there is the usual assembly of checkerwork 8.

The arch over that portion of the flue extending within the limits of the checker chamber is so constructed that approximately one-half, adjacent to the bulkhead 5, provides a permanent platform 10, level on top, for use in removing dust from the flues under the checkerwork, and the remainder built as a removable arch 12 which provides, by its removal during rebuilding, an inexpensive means of entry to the flues under the checkerwork.

45

40

50

55

55

- Beneath the end of the furnace having the removable bulkhead 5 is a conduit 14 which comprises the air or gas inlet and waste gas outlet of the checker chamber. This conduit 14 (air or gas inlet and waste gas outlet of the checker chamber) communicates with a space 15 which is immediately beneath the checkerwork 8 of the checker chamber and, accordingly, the space 6 which is immediately above the checkerwork.
- 10 The conduit 16, which comprises the heated gas or air inlet and the waste gas outlet of the furnace, is disposed above the level of the floor line 2.

According to the foregoing, it will be noted that 15 the "cold" or stack end of the checker chamber is that end which is beneath the removable bulkhead 5 and provided with the conduit 14 (air or gas inlet and waste gas outlet).

- The numerals 21, 22 and 23 respectively designate 20 the slag pockets, downtakes, and furnace interior. Waste gases escape from the furnace interior through the downtakes to the slag pockets and thence through the conduit, or connecting flue, 16 to the regenerator chambers. 25 Similarly combustion media preheated in the regenerator chambers to a high temperature pass from the regenerators through the conduit, or connecting flue, 16 to the slag pockets 21 and through the uptakes 22 to the furnace interior 23.

30 Among the advantages provided by the invention are the following:

- (1) During the rebuilding of the furnace and reconditioning of the checker chambers, no 35 checker-bricks are removed except those, usually in the top courses, which have been damaged by temperature or the fluxing action of waste gases or both.

(2) Vertical openings can be blown down with compressed air as at present.

- 40 (3) Horizontal openings, if present, can be blown out by constructing the division wall 7 with an opening opposite each horizontal passage through the checkerwork, these openings to be closed with a brick plug during normal operation or left open, if desired, to allow cleaning during the operating campaign.

45 (4) Dust which accumulates in the flues under the checkerwork during operating periods, or which is blown down from the checkers during the cleaning operation, can be removed from the furnace by taking out the bulkhead 5 at the "cold" end of the checker chamber and removing the removable arch 12, thus providing ready access to the flues and ample room for throwing 50 dust from flues to the permanent platform 10 and from the latter to the outside floor level through the opening afforded by the removable bulkhead 5.

55 (5) The provision of the permanent platform 10 eliminates the expense incident to the erection of a temporary scaffold in the checker chamber as required with conventional designs.

60 (6) The improved construction makes periodic cleaning of checkerwork, during the time the furnace is operating, a more thorough and effective operation as the checkerwork is more accessible. With the checkerwork removed some distance from the removable bulkhead 5, the cleaning pipes, introduced through the opening afforded by the bulkhead, are able to reach the 65 front corners of the checkers.

70 (7) The invention is also of value for improving distribution of both waste gases and air through the checkerwork of chambers which have been built with excessive length. Where excess-

sive length is present, the waste gases entering the checker chamber pass very largely down through the checkers at the "cold" end of the chamber, or that end most distant from the furnace, the amount of waste gas passing through the checkers diminishing in volume toward the hot end (furnace end) and very little going down in that part adjacent to the bridge wall, designated at 20.

The reason for this is believed to be that the 10 waste gas flue, connected to the "cold" end of the chamber 6, exerts the greatest influence for removal of waste gases at the "cold" end, this influence diminishing toward the "hot" end until entirely dissipated and there exists no influence 15 to draw gases through the checkers at the extreme or "hot" end in cases where the checker chamber is too long. The aspirating effect of the flow of gas over the bridge wall 20, in conjunction with its velocity, also works against passage of waste gas through checkers adjacent to the bridge wall as sufficient differential pressure does not exist between the top and bottom of the checkerwork to make the gases turn and flow downward in the area near the bridge 25 wall 20.

Likewise, after the furnace is reversed and the checker chamber used to preheat the air entering the "cold" end, the influence to draw air through the checkers is greatest at the "hot" or furnace end and least at the "cold" or stack end. Therefore, in a chamber of excessive length, most of the hot waste gases pass down the checkerwork adjacent to the so-called "cold" end and most of the air up through the checkers at the so-called "hot" end, thus eliminating the possibility of maximum heat transfer from waste gas to air through the medium of the checkerwork.

I have found that by shortening a checker chamber of excessive length in the manner referred to hereinbefore, an improved distribution 40 of air and gas through the checkers is achieved and better heat transfer is effected. The force acting to draw air or gas through the checkers, being confined in its effect to a reduced area, 45 causes hot gases to pass through the checkers closer to the bridge wall 20 and the incoming air to pass through closer to the division wall 7.

It is pointed out that at the so-called "cold" end of the checker chamber, the heat loss is the 50 greatest for the reason that four surfaces of the chamber are exposed on the "cold" end to room temperature. Therefore, by separating the end of the checkerwork from the bulkhead 5 on the "cold" end of the furnace, the heat transfer between the checkerwork 8 and the atmosphere outside of the checkerwork is reduced and the efficiency of the checkerwork as a heat transfer medium is improved.

Another advantage of the shortened checkerwork is that a greater differential pressure will be built up between the inlet and outlet of the checkers and therefore an improved distribution of gas or air will be effected.

While I have shown and described one specific 65 embodiment of the present invention, it will be seen that I do not wish to be limited exactly thereto, since various modifications may be made without departing from the scope of the invention, as defined by the following claims.

I claim:

1. In a regenerative furnace, a regenerative chamber having a fluid conduit communicating therewith, checkerwork in said chamber, a removable bulkhead adjacent the end of said re- 75

generative chamber which is remote from the furnace, said checkerwork being spaced from said removable bulkhead whereby there is formed a chamber between said removable bulkhead and the adjacent end of said checkerwork, a removable arch in the bottom of said chamber, and a division wall between said removable arch and the adjacent end of said checkerwork, said division wall being spaced from the roof of said furnace.

2. In a regenerative furnace, a regenerative chamber having a fluid conduit extending underneath the same, checkerwork in said chamber and in communication with said fluid conduit,

a removable bulkhead adjacent the end of said regenerative chamber which is remote from the furnace, said checkerwork being spaced from said removable bulkhead whereby there is formed a chamber between said removable bulkhead and the adjacent end of said checkerwork, the bottom of said chamber being closed from said fluid conduit and provided with a removable arch, and a division wall between said removable arch and the adjacent end of said checkerwork, said division wall being spaced from the roof of said furnace.

PEER D. NIELSEN.
